UNITED STATES PATENT OFFICE.

WILLIAM P. WAUGH, OF MONTCLAIR, NEW JERSEY.

GLAZING CONSTRUCTION.

1,156,335.

Specification of Letters Patent.

Patented Oct. 12, 1915.

Application filed March 16, 1912. Serial No. 684,205.

To all whom it may concern:

Be it known that I, WILLIAM P. WAUGH, a citizen of the United States, residing in the town of Montclair, county of Essex, and 5 State of New Jersey, have invented certain new and useful Improvements in Glazing Construction, of which the following is a specification.

This invention relates to improvements 10 in glazing construction and particularly to certain improvements in glazing bars and accessories for use in the construction of skylights, windows, greenhouses and the like.

15 My invention contemplates improvements in the glazing bar; in means for protecting the glass and holding it in position; in means for rendering joints weatherproof; in 20 means for protecting and preserving the packing material used and securing it against displacement both during construction and in the completed structure; improvements in condensation gutters and improvements in various other details of construction, as will be fully set forth herein- 25 after.

In the accompanying drawings which form a part of this specification, Figure 1 is a perspective view of a portion of a glazing bar embodying some of my improvements, showing portions of the panes of glass supported thereby, the bar being shown in this instance, for purposes of illustration, as particularly adapted for 30 skylight construction; Fig. 2 is a transverse sectional view of a well known form of glazing bar in combination with some of my improved features of construction; Fig. 3 is a transverse sectional view through an 35 other well known form of bar in connection with certain of my improvements; Fig. 4 is a longitudinal sectional view of a portion of the structure shown in Fig. 1 taken at the position indicated by the line IV—IV in Fig. 1; Fig. 5 is a side elevation of a structure of the form shown in Fig. 1, taken at a horizontal lap or joint between two panes of glass of a skylight, the glass being shown in section; Fig. 6 is a transverse section 40 through adjacent skylight bars taken at the position indicated by the line VI—VI in Fig. 5, one of the bars being the marginal bar of the skylight; Fig. 7 is a longitudinal sectional view through the lapped portions 45 of two panes of glass showing a retainer for

the packing strip between the panes; Fig. 8 is a perspective view of the retainer shown in Fig. 7; Fig. 9 is a view similar to Fig. 7 showing a modified form of retainer; Fig. 10 is a perspective view of a glass-holding 50 clip of the form shown in Fig. 5.

Referring to the drawings in detail, and particularly to Figs. 1, 4, 5, 6, 7, 8 and 10, the numeral 1 designates the main load-supporting member of my glazing bar, it 55 being provided with glass-supporting ledges 2 and being preferably in the form of a T, having its web 3 projecting upward between the edges of the panes of glass 4 supported on the ledges 2. The 60 panes of glass are retained on the ledges by means of the cap 5 which passes over the top of the web 3 and is secured thereto in any suitable manner, preferably by means of the U bolts 6 passing through holes 7 formed in 65 the web of the T. This general form of glass-retaining means is disclosed in an application of Thomas I. Duffy, Serial No. 465,320, filed November 30, 1908, and I therefore make no claim to the same broadly. 70 It is to be understood, however, that I do not wish to limit myself to this specific type of construction, except where the claims appended to this specification expressly call for the same. The U bolts 6 are provided 75 with nuts 8 and washers 9 interposed between which and the glass-retaining member or cap 5 are washers or cushions 10 of a yielding and resilient material, preferably a composition the principal ingredient of 80 which is ground cork. These washers provide a resilient connection between the cap and the glazing bar, and also prevent leakage through the holes in the cap through 85 which the ends of the U bolts pass. In 90 order to protect the cork washers 10 from possible damaging action of the weather, I may inclose the same in cup-shaped lead caps 11. These caps, while thoroughly protecting the washers from the weather, are 95 sufficiently soft and flexible to permit them to be crushed or telescoped by the screwing up of the nuts 8, so that they offer no resistance to the compression of the cork washers and the obtaining of the benefits of 100 the resilience of the latter. In some cases I may make the caps 11 of thin brass or other metal more rigid than lead, and include the washer 9 as an integral part of the cap. 105 The caps would in such case be made some- 110

what shallower than the resilient washer 10. The holes 7 through which the U bolts pass are preferably elongated, as shown in Fig. 4, in order to allow for the independent expansion and contraction of the cap 5 and supporting bar 1.

I may clamp the glass panes directly between the ledges 2 of the load-supporting bar and the cap 5, or I may embed the glass in putty in a well understood manner, but under most conditions either of these procedures is highly objectionable, as, owing to the irregularities in the surface contour of commercial skylight glass, it is impossible for the glass to find an even bearing surface, and it is consequently unevenly stressed. When putty is interposed, it is not only liable to crack and fall away, but it hardens to such an extent that it affords no yieldable cushion for the glass. The inevitable result is an excessive breakage of glass throughout the life of the structure. Such breakage is naturally particularly marked where the building is subjected to vibration, as in the case of train-sheds and most factory buildings. Moreover, packing must be inserted between the cap and the glass in order to render the joints leakage proof. I therefore interpose resilient material between the supporting ledges and the glass and between the glass and the cap, as shown in Fig. 1. I have discovered that the material best adapted for this purpose consists of strips of finely ground cork composition, such strips being shown at 12 between the glass-supporting ledges and the glass, and at 13 between the glass and the cap. I do not claim the use of cork composition for this purpose broadly in the present application, as the same is claimed in my application Serial No. 540,964 filed January 29, 1910. The cork composition of which I make these strips may be prepared in any of the well known ways for preparing such material. The material used for cork carpets is admirably adapted to my purposes. I prefer, however, to treat the material, during or subsequent to the process of manufacture, with both preservative and fireproofing agents. As a preservative, the material may be treated with creosote or its equivalent. Any of the well known processes for fireproofing wood may be utilized to fireproof the cork composition; for example, the "silicate," "sulfate and phosphate of ammonia," or "ammonium of carbonate" process may be employed. My material when thus treated is exceedingly effective, not only insures uniform glass bearings and weatherproof joints, but possesses great durability and forms with the glass an effective barrier against damage by fire. My material, when so treated, is superior to the lead packing strips sometimes used, as the lead melts at a comparatively

low temperature and runs out, leaving the joint loose and allowing tongues of flame to enter, while materials such as felt or oakum, which are also sometimes used for packing purposes, are obviously not fire-resistant.

A most important advantage of my cork composition strips lies in their superior qualities as a glass-bedding material. They can be made of an absolutely uniform thickness and thus give the glass continuous and uniform support throughout its length. They possess the necessary shock-absorbing resilience to the nicety of degree required, which resilience is permanent. They may be easily manipulated, are free from lumps, have but little porosity, so that no capillary attraction occurs, and are not readily attacked either by the weather or by any of the fumes prevalent in various manufacturing establishments, round-houses, and train-sheds. In all of these respects my cork composition is superior to any of the other packing materials which have been used for a like purpose, with which I am familiar. Lead is objectionable in case of fire, as above pointed out, and also because it has no resilience, but having been once pressed down by the glass it is incapable of resuming its initial shape upon the releasing of the pressure to which it is subjected, as in case of the temporary displacement of the glass. It does not give the glass the resilient and shock-absorbing support required if the glass is to be preserved against breakage because of vibration of the building. Rubber has also been used for a packing material, but this is unsatisfactory as it vulcanizes and deteriorates rapidly with exposure to the weather, becoming hard and brittle instead of remaining elastic. It is also seriously affected by fumes. Felt, asbestos and oakum are unsatisfactory as glass-bedding materials, as it is practically impossible to lay them evenly, lumps invariably occurring from place to place which subject the glass to uneven stresses, and they absorb moisture. These materials also rapidly mat down until their initial resilience almost entirely disappears. They also absorb moisture and are likely to deteriorate from the effects of the weather and of fumes.

In addition to the strips 12 and 13 of cork composition, I preferably interpose additional portions of the same material between the edges of the glass and the web 3 of the load-supporting member. These portions may be short pieces 14, as shown in Fig. 4, placed at suitable intervals, or they may take the form of continuous strips 15, as shown in Fig. 5. These strips or pieces, which I term "anti-expansion spacers", prevent the glass from sliding laterally or expanding into contact with bolts or metal of any kind, particularly the metal load-sup-

- porting bar, with the consequent risk of being broken by such contact. They prevent the chill of the glass being transmitted to the bar in case of contact, causing condensation to form on the same. And they also retain the strips 13 in position, as will be hereinafter explained. In case the continuous strips 15 are used, they serve as an additional protection against leakage.
- 10 In building up a skylight or window according to my improved construction, I may simply lay the several strips of cushioning material in their respective positions, or I may secure them to the load-supporting member and the glass, respectively, by means of a suitable cement, shellac, glue, or binder. I may, however, either in addition to an adhesive or in place thereof use metal clips or cork holders 16 for retaining the bedding strips 12 and the spacers 14, or 15, as the case may be, in position. As shown in Figs. 1 and 4, these clips 16 pass over the top of the web 3, the lower ends of the two legs of the clips being bent to form shoulders 17 which support the strips or spacers 14 or 15, the portions of the cork holders beyond these shoulders being bent outwardly to form flanges 18 over which the strips 12 pass. These flanges 18 are provided with means to retain the strips 12 against displacement, these means in the form shown in Figs. 1 and 4 consisting of one or more prongs 19 struck up from the flanges. The cork composition strips are retained in position by simply being pressed down upon these prongs. The cork holders 16 are preferably comparatively short pieces, as shown in Fig. 4, they being disposed at suitable intervals throughout the length of the bar.
- 40 For engagement with the strips 13 resting on the upper surfaces of the panes of glass, the cap 5 is provided with horizontal bearing surfaces 20, the edges of which, 21, are flanged over to retain the strips 13 against outward movement, and also to protect the latter from the weather and sliding ice. These flanges 21 preferably do not extend at right angles to the surface of the glass, but are flared outward, as shown, and the strips 13 are made of such thickness that they cannot be compressed to such an extent that the edges of the flanges 21 will engage or touch the glass and cause it to be chilled through the agency of frost. Tightening the nuts 8 on the U bolts 6 draws the legs of the cap 5 toward each other and moves the strips 13 inwardly until they press resiliently against the spacers 14 or 15 by which further movement of the strips 13 is retarded and their inner edges are prevented from slipping upwardly. The screwing up of the nuts 8 also serves positively to draw down the cap 5 in the direction of the glass, and thus permits the desired pressure to be exerted upon the glass through the resilient strips and produces a perfectly water-tight joint.
- Where my glazing bar is to be used in skylight construction, I may provide the same with gutters to carry off the condensation which may collect on the under-surface of the glass, and also to take care of any possible leakage around the edges of the glass. I may use any well known construction of gutter, but I prefer to use the improved form of gutter shown in Figs. 1, 5 and 6. According to this construction, a pair of gutters 22 are provided, each gutter having a horizontal shoulder 23, which seats upon one of the glass-supporting ledges 2, 80 and an upturned flange 24 at the inner edge of this shoulder, which lies in contact with a side of the web 3. These flanges preferably extend higher than the upper surface of the glass, so that if any leakage takes place between the upper surface of the glass and the packing strips 13, such leakage will be caught by this flange and the shoulder and will eventually find its way out either under the bedding strip 12 and into 85 the gutter, or through the channels 25. These flange portions 24 lie inside of the legs of the clips or cork holders 16 which thus serve to retain the gutters in position upon the bar. The shoulders 17 of the clips or cork 90 holders support the strips 14 or 15 above the glass-supporting ledges and thus provide channels 25 which serve to conduct away any leakage which may come in above the glass along the bar. This leakage, if any, could not therefore increase the moisture in the interior atmosphere of the building, or the quantity of condensation forming on the inner side of the glass, which is very important. Beyond the shoulders 23 of the 100 gutters 22 are the necessary downward, outward and upward legs to form the gutters proper. The upper leg is preferably bent at an angle of about forty-five degrees to the horizontal leg in order to provide sufficient depth without approaching too nearly to the glass surface to prevent the passage of the condensation water from the inner glass surface to the gutter.
- Figs. 5 and 6 show the construction used 115 where two panes of glass overlap to form a horizontal joint, as in a skylight. Where a joint of this construction is to be made the load-supporting bar is kinked or offset, as indicated. The upper pane of glass 26 is 120 extended down over the lower pane of glass 4 for a short distance, both panes being supported at their lateral edges upon the bedding strip 12 which is preferably continuous, following the contour of the offset 125 glass-supporting ledge. The cap 5 is preferably made in sections, the upper section being carried down to overlap the lower section. Both panes of glass are held in position in any suitable manner, but preferably 130

4
by means of glass-holding pieces 27, shown in detail in Fig. 10. These pieces comprise members 28 adapted to be bolted or wired to the web 3 of the load-supporting bar by means of bolts 29, and members 30 which rest upon the upper surface of the glass, these members having at their ends bent over portions 31 forming hooks to engage the edges of the glass and retain the glass against slipping down longitudinally of the load-supporting bars. These glass-holding pieces are preferably made of material of low thermal conductivity, such as sheet iron coated with lead. This prevents chilling of the glass which often causes the glass to crack and also tends to increase the formation of frost on the glass.

In order to close the space between the lapped end margins of the panes of glass, I insert between the overlapping margins a packing strip 32 which is preferably made of cork composition, such as used for the glass-bedding strips. This strip is so placed as to leave a cross gutter above it for the condensation from the upper pane. In order to retain this packing strip in position, I utilize one or more retaining clips 33 spaced at intervals along the ends of the panes. Figs. 7 and 8 show one form of these retainers. The retainer is provided at one end with a hook 34 adapted to overhang the upper edge of the lower pane, and at the other end with an upturned flange 35 preferably formed for greater strength by folding the metal upon itself, as shown. This flange 35 engages the lower edge of the upper pane, so that the retainer is held against movement in either direction. These retainers will stretch sufficiently to permit the glass panes to expand independently of each other in the direction of their length. They are preferably made of material of low thermal conductivity such as lead-coated sheet metal, as are the glass-holders 27. In order to secure the packing strip to the retainer, the latter may be provided with a prong 36 punched out of the metal of the retainer. These retainers serve to hold the packing strips in position while the structure is being assembled, and also to prevent the packing strips from slipping out by reason of vibration or gravity, but it is also very desirable to hold the packing strips against movement in the upward longitudinal direction of the skylight, so as to prevent them from being blown from between the glass panes by the wind. It is for this reason that I make the flange 35 extend high enough to engage the lower edge of the upper pane of glass and provide the prong 36 to prevent the above described upward movement of the packing strip.

In Fig. 9 I have shown a modified construction of retainer in which, instead of providing a prong 36 upon which the pack-

ing strip is to be pressed down, I form an intermediate flange 37 in the retainer, between which and the flange 35 the packing strip is gripped. The distance between the flanges 35 and 37 is preferably such that the strip 32 has to be pressed into place between them, which causes it to be held firmly in position during construction.

Fig. 6 shows at the left a bar 38 of a form adapted to be used at the margin of a skylight or window. An angle bar is used for this purpose instead of a T bar, and the cap 39 is provided with one inclined leg and a vertical leg 40.

In Fig. 2 I have shown certain features of my invention used in connection with a standard form of sheet metal skylight bar 41. The bar shown in this figure comprises a central vertical member 42 to which is secured a sheet metal member 43, which is folded upon itself to form gutters 44, the upper portions of this member being bent at right angles to the member 42 to provide glass-supporting ledges 45. The edges of these glass-supporting ledges are flanged up as indicated at 46, channels being thus formed to receive and retain the bedding strips 12. The strips 13 are held in engagement with the upper surfaces of the panes of glass 4 by means of a cap 47 which is secured to the member 42 by means of rivets 48, or in any other suitable manner. Clips 49 are provided at intervals to support the spacing pieces or strips 50 above the glass-supporting ledges 45 in order to provide channels 25 through which possible leakage may be conducted away. These clips 49 may have the lower ends of their horizontal portions turned upward a short distance, as indicated at 60, in order to prevent the spacers 50 from slipping off.

In Fig. 3 I have shown features of my invention applied to another standard form of sheet metal glazing bar. The glazing bar shown in this figure comprises the central member 51 which is surrounded by sheet metal bent outwardly at 52 to provide glass-supporting ledges, the sheet metal being folded upon itself at the bottom of the bar to form gutters 53. The glass bedding strips 12 are held in position by means of clips 54, which are provided with shoulders 17 to support the spacing portions or strips 14. The edges of the horizontal portions of the clips 54 are turned up to form flanges 55 which retain the strips 12, these flanges being used in place of the prongs 19 shown in Figs. 1 and 4. The panes of glass are retained in position by means of a cap 5 and strips 13 of the form shown in Fig. 1.

While I have shown in the drawings and described in detail in this specification certain preferred embodiments of my invention, it is to be understood that these embodiments are intended to be merely illustrative

of the principles of my invention and that my invention may be embodied in many other structures.

Having thus described my invention, I 5 claim:

1. In glazing construction, a load-supporting member comprising a T bar, the web of which extends outward between the edges of panes of glass to be supported by said bar, the flanges of said bar forming glass-supporting ledges, strips of waterproofing, non-capillary material supported on said ledges, panes of glass supported on said strips, second strips of said material resting 10 on said panes of glass, third pieces of said material inserted between the edges of said panes and the web of the load-supporting bar, the inner edges of said second strips abutting against said third pieces, and a 15 glass-retaining cap extending over the top of the web of the load-supporting bar, and adapted to exert pressure both downwardly and inwardly on said second strips.
2. In glazing construction, a load-supporting bar having glass-supporting surfaces, strips of glass-bedding material resting upon each of said surfaces, and means for retaining said strips in position comprising clips, the end portions of which rest upon said 20 glass-supporting surfaces under said strips, said end portions having portions struck up therefrom and entering the glass-bedding material.
3. In glazing construction, a load-supporting member comprising a web and a glass-supporting ledge, a strip of glass-bedding material resting upon said ledge, and means for retaining said strip in position comprising a clip, a portion of which is bent 25 over said web, another portion of said clip being provided with means for engaging said strip.

4. In glazing construction, a load-supporting member comprising a web and a glass-supporting ledge, a strip of resilient glass-bedding material resting upon said ledge, and means for retaining said strip in position comprising a clip, a portion of which is bent over said web, the end portion of said 30 clip passing between said ledge and said strip and being provided with means to prevent lateral movement of the strip.

5. In glazing construction, a load-supporting member comprising a web and a glass-supporting ledge, a strip of glass-bedding material resting upon said ledge, and means for retaining said strip in position comprising a clip, a portion of which is bent over said web, the end portion of said clip passing between said ledge and said strip and being provided with a prong struck up therefrom and entering the material of the strip.

6. In glazing construction, a load-supporting member comprising a web, and glass-sup-

porting ledges extending laterally therefrom, a strip of glass bedding material resting upon each of said ledges, and means for retaining said strips in position comprising a clip passing over said web, the end portions of said clip being bent outward and extending between said strips and said ledges and being provided with means to prevent lateral movement of said strips.

7. In glazing construction, a load-supporting bar comprising a web and a glass-supporting ledge, a glass-bedding strip resting upon said ledge but spaced from said web, a pane of glass resting upon said bedding strip, a spacer of resilient material inserted 70 between said web and the edge of said glass, and means for supporting said spacer above said ledge, whereby a channel is formed between the edges of said bedding strips and said web and between said spacing portions 80 and ledge.

8. In glazing construction, a load-supporting bar comprising a web and a glass-supporting ledge, a glass-bedding strip resting upon said ledge, but spaced from said web, a pane of glass resting upon said bedding strip, a spacing piece of resilient material inserted between said web and the edge of said glass, and means for supporting said spacing strip above said ledge, said means 90 comprising a clip, a portion of which is bent over the edge of said web, said clip having a portion bent laterally away from said web to form a shoulder upon which said spacing 95 piece rests.

9. In glazing construction, a load-supporting member comprising a web having glass-engaging ledges extending laterally therefrom, strips of resilient glass-bedding material resting on said ledges, but spaced from said web, panes of glass resting on said strips, means for retaining said panes in engagement with said strips, spacing pieces of resilient material inserted between the edges of said panes and said web, and clips comprising pieces of sheet metal extending over the edge of said web, the legs of said clips being each bent away from said web near said ledges to form shoulders upon which said spacing pieces rest, the portions of said clip beyond said shoulders engaging said bedding strips and being provided with means to prevent lateral movement of the same.

10. In glazing construction, a load-supporting member comprising a web having glass-supporting ledges extending laterally therefrom, glass-bedding strips resting upon said ledges, but spaced from said web, panes of glass resting upon said strips, moisture excluding strips engaging the surfaces of said panes of glass, a cap extending over said web and having portions engaging said second strips, means for securing said cap to said web, spacing pieces of resilient ma- 120
125
130

- terial inserted between said web and the edges of said panes of glass, the edges of said second strips engaging said spacing pieces, and clips passing over said web and 5 between the same and said spacing pieces, portions of said clips being bent away from said web near said ledges to form shoulders upon which said spacing pieces rest, the portions of said clips beyond said shoulders 10 being bent into engagement with said ledges and passing between said ledges and said bedding strips, said portions being provided with means to engage said bedding strips and prevent lateral movement of the same.
- 15 11. In glazing construction, a load-supporting bar comprising a web and a glass-supporting ledge, a gutter mounted at the edge of said ledge, said gutter having a horizontal flange or shoulder resting upon said 20 ledge, and an upturned flange adjacent to said web, a clip having a portion hooked over said web, and a portion engaging said upturned flange, a strip of glass-bedding material resting upon said horizontal shoulder, a pane of glass resting upon said strip, and means for retaining said glass in engagement with said strip.
12. In glazing construction, a load-supporting bar comprising a web and a glass-supporting ledge, a gutter mounted at the edge of said ledge, said gutter having a horizontal flange or shoulder resting upon said ledge, and an upturned flange adjacent to said web, a clip having a portion hooked 30 over said web, and a portion engaging said upturned flange, a strip of glass-bedding material resting upon said horizontal shoulder, a pane of glass resting upon said strip, means for retaining said glass in engagement with said strip, a spacing piece of 35 resilient material inserted between the edge of said glass and said web, said clip passing between said spacing piece and said web, a portion of said clip near said ledge being bent away from said web to form a shoulder 40 upon which said spacing piece rests, the end of said clip being bent away from said web 45 and passing between said glass-bedding strip and the horizontal shoulder portion of said gutter and being provided with means to engage said glass-bedding strip and prevent lateral movement of the same.
13. A clip for retaining a packing strip between overlapping panes of glass comprising a straight body portion having one end bent away to form a hook and a flange at the other end thereof extending in the opposite direction from said hook and adapted to engage and position the edge of a pane of glass, a projection extending from said body portion in the same direction as said flange and between the flange and the hook, and a shoulder extending beyond said flange and in the same plane as the body portion.
14. A clip for retaining a packing strip between overlapping panes of glass comprising a straight strip of sheet metal having one end bent away to form a hook, and a flange formed by folding the other end thereof, said flange extending in the opposite direction from said hook and being perpendicular to the body portion and adapted to engage and position the edge of a pane of glass, the end of the strip adjacent to the folded extending beyond said flange and in line with said body portion.
15. In glazing construction, a ledge-supporting member comprising a web and a glass-supporting ledge, a strip of ground cork composition upon said ledge, a pane of glass bedded upon said strip, and a clip for holding said pane of glass in position, said clip being formed of sheet metal coated with lead and comprising a vertical member secured to the web of said load-supporting member, and a horizontal member engaging the surface of the pane of glass, said horizontal member having an extension hooked over the under-edge of said pane.

WILLIAM P. WAUGH.
